C. L. SCHWARTZ.
RAILWAY CAR.
APPLICATION FILED APR. 8, 1909.

935,696

Patented Oct. 5, 1909.

UNITED STATES PATENT OFFICE.

CARL L. SCHWARTZ, OF ST. LOUIS, MISSOURI, ASSIGNOR TO COMMONWEALTH STEEL COMPANY, OF ST. LOUIS, MISSOURI, A CORPORATION OF NEW JERSEY.

RAILWAY-CAR.

935,696.

Specification of Letters Patent.

Patented Oct. 5, 1909.

Application filed April 8, 1909. Serial No. 488,633.

To all whom it may concern:

Be it known that I, CARL L. SCHWARTZ, a citizen of the United States, residing at St. Louis, in the State of Missouri, have invented a new and useful Improvement in Railroad-Cars, of which the following is a specification.

My invention relates particularly to the coupler-stop and coupler draw-bar carry-iron in connection with a railroad car, and has for its object to provide a strong, durable, and resilient coupler-stop specially adapted for the attachment, preferably thereto, of a draw-bar carry-iron having the level of its bearing surface adjustable in relation to that of its points of attachment.

It consists in features of novelty as hereinafter described and claimed, reference being had to the accompanying drawing forming part of this specification, whereon,

Figure 1, is a front elevation of my improved coupler-stop and combined carry-iron support as applied to a car underframe (broken away); Fig. 2, a top plan view 25 thereof; Fig. 3, a vertical transverse section therethrough on line 3-3, in Fig. 1, and Fig. 4, a perspective view of a modification of the carry-iron.

Like letters and numerals of reference denote like parts in all the figures.

a represents my improved coupler-stop which is composed preferably of cast steel integral throughout and consists preferably of a rear plate 1 which is adapted to bear 35 against the outer face of the end sill *b* of the car to which it is secured by the truss-rods 2 in the usual manner, the plate 1 being preferably formed in the middle at the top with a rearwardly projecting horizontal flange 3 which overlaps and bears upon the top of 40 the sill *b*, to which it is fixed by a lag screw (or bolt) 4, the plate 1 being furthermore formed at a suitable distance from the flange 3 at each side thereof, with an extended portion 1' which projects upward from the top edge of the plate 1 and is adapted at its rear side to bear against the corresponding end post 5 (indicated by dotted lines) of the car.

50 The body of the coupler-stop *a* which projects forward from the rear plate 1, consists preferably, of two opposite brackets *c* arranged at a suitable distance apart, one on each side of the longitudinal center of the car and having their lower portions 6, which

are below the bottom edge of the plate 1, bifurcated in the same plane for the attachment thereto, preferably at the bottom, of the vertically adjustable carry-iron *d* as hereinafter more particularly referred to, 60 for supporting the coupler-shank or draw-bar 7 which rides thereon midway between the brackets *c* as shown. In the upper portion 6' of each bracket *c*, immediately in front of the rear plate 1, is formed an upright pocket 8 which is closed on all sides except at the top and at its inner side, opposite to the corresponding open side of the pocket 8 in the other bracket *c*, the outer wall 9 of each pocket 8 opposite to its said 65 open side being united to the rear plate 1, and preferably to the corresponding extension 1' thereof, by a strengthening rib 10. Within the pockets 8 thus formed are inserted from above the end portions of a series of spring plates *e* arranged preferably, without camber, flatwise against each other and spanning the space between the pockets 8 in front of, but clear of the rear plate 1, 70 for receiving and resiliently resisting the 75 concussion of the coupler striking-plate 11 which strikes against the front side of the spring-plates *e* when "buffing".

The carry-iron *d*, which in its assembled position extends between the depending sides 85 of its supports 6, is formed at one end preferably, with two laterally projecting studs or trunnions 12 which are adapted to pivotally engage in bearings 12' formed therefor in the sides of the corresponding supports 6, 90 while the other end of the carry-iron *d* is preferably perforated and a coupling pin 13 inserted therethrough and through corresponding bearings 13' formed therefor in the sides of the opposite support 6, the distance 95 between the upper side of the carry-iron *d* and the horizontal center line through its bearings or points of attachment 12', 13', in the assembled position of the parts as shown on the drawing, being less than the 100 distance between the said line and the underside of the carry-iron *d*, whereby, when owing to the set of the truck-springs, the draw-bar 7 drops accordingly, the normal level of the latter is restored by reversing the position of the carry-iron *d* in its bearings 12', 13', or as indicated by dotted lines in Fig. 1.

In the modified carry-iron *d'* shown by Fig. 4, the top and bottom sides *x* and *y* thereof, which correspond to the top and bot-

tom sides of the carry-iron d seen in Fig. 1, are formed with trunnions 14 and perforations 15, similar to 12 and 13, the trunnions 14 and perforations 15 being so arranged 5 that, when the carry-iron d' is mounted thereby in the bearings 12', 13', of the coupler-stop a , or equivalent member of the car underframe, the distance between the longitudinal center line through the said bearings 10 to the then top side a' of the carry-iron d' will be less than the distance between the side line and the top side of the carry-iron d in Fig. 1, or in other words, by using the carry-iron d' the maximum adjustment of 15 the carry-iron d may be graduated.

In the above construction, by attaching the carry-iron d (or d') to the supports 6 forming rigid parts of the coupler-stop a , a firm and level bearing of the coupler-shank 20 or draw-bar 7 in its vertically adjusted positions thereon is insured and maintained; also, by the upward extensions 1' of the dead-block a against the front sides of the car end posts 5, protection thereto at the base is 25 afforded, and furthermore, by the resilience of the leaf spring e forming a part of the coupler-stop, the impact of the coupler when "buffing" is imparted more gradually to the body of the stop a than when received directly by the latter as in the ordinary construction.

Another advantage of my invention is, that when, owing to the wear of the wheel-tires and set of the truck-springs, causing a 35 general settling of the car supporting members, the coupler-shank or draw-bar approaches too closely to the track, its normal level may be restored by a corresponding vertical adjustment of the draw-bar carry-

40 iron.

What I claim as my invention and desire to secure by Letters Patent is:—

1. In a railroad car, the combination of a coupler draw-bar carry-iron adapted to be

attached thereto, and means for vertically 45 adjusting the level of the carry-iron relatively to its points of attachment to the car, substantially as described.

2. In a railroad car, the combination with two opposite appendant members thereof, of 50 a spring element adapted to span the space between, and to be held by the said members clear of the end of the car, for engagement by the coupler striking-plate, a coupler draw-bar carry-iron adapted to span the said 55 space and to be attached to the said members, and means for vertically adjusting the level of the carry-iron relatively to its points of attachment to the said members, substantially as described. 60

3. In a railroad car, the combination with an appendant member thereof, comprising a plate adapted to bear against the end sill of the car, and two opposite brackets projecting forward from the said plate, one on each 65 side of the longitudinal center of the car, of a spring element adapted to span the space between, and to be held by the said brackets clear of the said plate, for engagement by the coupler striking-plate, a coupler draw-bar 70 carry-iron adapted to span the said space and to be attached to the said brackets, and means for vertically adjusting the level of the carry-iron relatively to its points of attachment to the said brackets, substantially 75 as described.

4. In a railroad car, the combination with two opposite appendant members thereof, of a spring element adapted to span the space 80 between, and to be held by the said members clear of the end of car for engagement by the coupler striking-plate, substantially as described.

CARL L. SCHWARTZ.
